2 SHEETS—SHEET 2.

UNITED STATES PATENT OFFICE.

MIKE CAPPELLI, OF WASHINGTON, PENNSYLVANIA

COKE-OVEN DOOR.

1,159,827.

Specification of Letters Patent.

Patented Nov. 9, 1915.

Application filed August 30, 1913. Serial No. 787,530.

To all whom it may concern:

Be it known that I, MIKE CAPPELLI, a citizen of the United States, residing at Washington, in the county of Washington and State of Pennsylvania, have invented certain new and useful improvements in Coke-Oven Doors, of which the following is a specification.

This invention relates to improvements in coke ovens and has for its object to provide a door for coke ovens consisting of metal frames and brick fillers having means for protecting the frames from the heat in the ovens.

Another object of the invention is to provide a coke oven door formed of a metal frame and brick fillers, said fillers being removable.

With the above and other objects in view, which will be more fully explained in the following specification, I have invented the device illustrated in the accompanying drawings in which—

Figure 1 is a front elevation of my improved coking oven, Fig. 2 is a section taken on line A—A of Fig. 1, Fig. 3 is a side elevation of the door frame removed from the oven, Fig. 4 is a section on line B—B of Fig. 5, Fig. 5 is a detail front elevation of a door showing the fire bricks partly removed, Fig. 6 is a rear elevation of a lower door with fire bricks removed, Fig. 7 is an elevational view of a wedging member, and Fig. 8 is a modification of a part to be described.

Like reference characters indicate like parts throughout the specification and in the various views in the drawings in which—

1 indicates a coking oven having a metal door frame 2 the inner edges of which are entirely covered by the masonry 3 so as to protect the metal from the action of the heat within the oven. Hinged to the outer edges of said frame are a series of doors 4 and 5 which are upper doors and 6 and 7 which are the lower doors. Each of these doors are similar in construction and consists of a frame 8 having a vertical central bar 9 and flanges 10, 11 and 12, the latter two being vertical. Seated between said flanges 10, 11 and 12 and forming closures for the openings 13 and 14 are fire bricks 15 and 16 having flanges 16', 17 and 18 and one of the fire-bricks has a semi-cylindrical groove 19 in its edge 20 and the other having a similar groove 21 opposing said first groove. The

edges 22 and 23 of said bricks 15 and 16 are inclined to conform to the inclination of said flanges 11 and 12 so as to form a dove-tail connection therewith. The flanges 16' and 17 of the brick are adapted to cover the edges 24 and 25 of the flanges 10 and 11 and 12 after said bricks are slid into position between said latter flanges. A locking member 26 is adapted to seat between the flanges 18 and 19 and the frame 8 and be held in position seated on the upper edge of said brick by means of tapering pins 27 adapted to project through openings 28 in said frame 8 and into tapering openings 29 in said member 26. The pins 27 are provided with openings 30 which are adapted to project partly outwardly of the frame 8 so that by means of a wedge member 31 said pins may be removed at will in order to release the member 26. It will be seen that the fire bricks 15 and 16 will be so mounted in their bearings that their inner edges will be suitably separated and that an opening 32 is provided in the member 26 which alines with the semi-cylindrical grooves 20 and 21 through which member 33 may be projected into the cylindrical opening 34 formed by said grooves 20 and 21, the member 33 being cylindrical and of a greater diameter than the bore or opening 34, and tapering at its lower end 35 it is adapted to force the bricks 15 and 16 apart causing them to be wedged in the door frame 8 so that they cannot be removed without first removing the member 33, and then the member 26.

Seated between the frame 8 and the brick 15 and 16 are bars 36, 37 and 38 each having offsets 39 whereby air spaces 40 are formed between the frame 8 and the fire brick so as to keep as much heat as possible from the frame 8. If desired, for the purpose of effectively holding the parts of the swinging doors in position the tie bolts 35' may be used, adapted to clamp the fire-bricks closely against the frame-work of the door.

The hinge members 41 and 42 are offset from the frame 2 and doors 4, 5, 6 and 7 for the purpose of allowing said doors to open wide.

When the bricks in one of the doors have become burned out they can readily and quickly be renewed by removing the plate 26 and then sliding into position another pair of bricks as illustrated in Fig. 5. By means of my invention the flames and heat in the oven are kept out of direct contact with

the metallic frames of the doorway and doors and consequently these frames will last indefinitely.

Having now described my invention, that 5 which I claim to be new and desire to procure by Letters Patent is:—

1. A coke oven door consisting of a frame having flanges on its bottom and two vertical sides, a pair of fire bricks adapted to seat between said flanges, a removable cover for said bricks, said bricks having flanges adapted to cover the edges of said first flanges and the edge of said cover, spacers for holding said bricks from contact with said frame, and a wedge adapted to force said bricks apart whereby they are bound in position in said frame.
2. In combination in a coke oven, two vertically disposed doors, an inner lining of fire brick arranged in each of said doors, said bricks being held in place by a dove-tailed connection, and a wedge interposed between said fire-bricks to force them asunder in said doors.
3. A coke oven door consisting of a frame having flanges on its bottom and two vertical sides, a pair of fire bricks adapted to seat between said flanges, a removable cover for said bricks, said bricks having flanges adapted to cover the edges of said first

flanges and the edge of said cover, spacers for holding said bricks from contact with said frame, and a wedge adapted to force said bricks apart whereby they are bound in position in said frame, said wedge adapted to hold said cover in position.

4. A coke oven door consisting of a frame having inclined vertical flanges, a vertically divided fire brick having inclined outer vertical edges seated in said frame between said flanges and a wedge adapted to bind said brick in said frame, said brick members having opposing grooves in their inner edges to receive said wedge.

5. A coke oven door consisting of a frame having inclined vertical flanges, a vertically divided fire brick having inclined outer vertical edges seated in said frame between said flanges and a wedge adapted to bind said brick in said frame, said brick members having opposing grooves in their inner edges to receive said wedge, said brick having flanges adapted to cover the flanges of said frame.

In testimony whereof I affix my signature in presence of two witnesses.

MIKE CAPPELLI.
